UNITED STATES PATENT OFFICE.

JOHN T. FETHERSTON, OF NEW YORK, N. Y., ASSIGNOR OF ONE-HALF TO POWER SPECIALTY COMPANY, OF NEW YORK, N. Y., A CORPORATION OF NEW YORK.

FURNACE-FEEDING APPARATUS.

1,053,020.

Specification of Letters Patent.

Patented Feb. 11, 1913.

Application filed February 2, 1910. Serial No. 541,503.

To all whom it may concern:

Be it known that I, JOHN T. FETHERSTON, a citizen of the United States, residing at New York, in the county of Richmond and State of New York, have invented certain new and useful Improvements in Furnace-Feeding Apparatus, of which the following is a full, clear, and exact description.

This invention relates to furnace-feeding apparatus, more particularly for so-called "destructor" furnaces in which household refuse and other waste materials are consumed, and has for its chief object to provide power-actuated means for the purpose 15 which shall be simple in construction and thoroughly effective in operation.

To this and other ends the invention which I desire to cover consists in the novel features and combinations of elements hereinafter described.

The preferred embodiment is illustrated in the annexed drawings, and referring now thereto, Figure 1 is a plan view of the apparatus. Fig. 2 is a side elevation, partly 25 in section. Fig. 3 is a cross section on a larger scale, taken on line 3—3 of Fig. 1, but with the scraper or unloading device in an advanced position.

The furnace is shown diagrammatically 30 at 4, and is provided with a suitable opening 5 through which the material is introduced, and back of this opening the feeding or charging apparatus is arranged.

The main element of the feeding apparatus 35 is a rectangular charging frame the sides of which are formed by two channel irons 6, 6, having their flanges disposed inwardly. At the front the side members mentioned are connected by a bottom plate 40 7, so that the forward portion of the structure constitutes a receptacle or pan for the material which is to be introduced into the furnace. This pan, practically as wide as the furnace, is open at the front, and extending across the pan is a movable wall or 45 follower 8, normally resting against two stops or abutments 9, 9, mounted on the inside of the side members near the back of the bottom plate 7, as shown in Figs. 1 and 2. At the rear side plates are connected by 50 a transverse member 10, and the whole is mounted on a series of supporting frames 11, provided with rollers 12 on which the side members 6 rest, and with rollers 13 bearing the sides of said members to pre-

vent sidewise displacement of the charging frame. The latter can therefore be run into the furnace, and withdrawn, through the opening 5, at will. If desired, rollers 13^a may be provided, arranged over the 60 side plates and carried by one or more of the frames 11.

At the rear of the charging frame is a ram 14 of any convenient and suitable type, having the forward end of its plunger 15 65 secured to a cross plate 16 the ends of which are secured to the side plates 6, 6. Mov-able longitudinally through this cross plate 16 are two rods 17, secured at their forward ends to the follower 8 and connected at their 70 rear ends to suitable counterweights 18, 18, by means of cables or ropes 19, 19 running over pulleys 20, 21. The function of the counterweights is to retract the rods and the follower, as will be readily understood, 75 but this movement of retraction relative to the pan is limited by two stops 22, 22, mounted on the rods and arranged to en-gage the cross plate 16, thereby preventing further backward movement. 80

Pivoted on each stop is a finger or catch 23, having a forwardly extending weighted arm 24, which serves to prevent forward movement of the finger on its pivot and to restore the same to its upright position 85 after rearward movement, as will be readily understood. On the frame 11 nearest to the furnace is a member 25 (not shown in Fig. 1) extending across and above the charging frame, and carrying two pivoted stops 26 90 arranged in the path of the catches 23, as shown in Fig. 3. These stops are pivoted to swing in a transverse plane, and each has a lateral extension or lug 27. The weight of the stop holds them in the posi-95 tion shown, with the lugs 27 in the path of two camming devices 28, having forwardly and rearwardly inclined faces, mounted on the side plates 6, 6, a short distance from the forward ends thereof. 100

From the foregoing the operation of the mechanism will now be readily understood. The parts being in the position shown in Fig. 1 and shown in full lines in Fig. 2, the pan is filled with the material which is to 105 be introduced into the furnace and is started. The entire charging frame is thereby advanced, the follower 8 being ad-vanced also by the transverse member 16 engaging the stops 22, and the stops 26 be-110

ing cammed inwardly by the members 28 out of the way of the latter. As the pan moves to the position shown in dotted lines in Fig. 2, inside the furnace, the fingers or catches 23 engage the stops 26 and are thrown back as they pass under the stops, after which the catches are restored to their initial positions by the weights 24. When the dotted line position is reached the ram 10 is reversed and the entire charging frame is retracted, but the follower, arriving at the stops 26, is arrested by the fingers 23 engaging the stops. The pan, however, continues its rearward movement, thereby causing the material to be scraped off over the forward edge of the pan into the furnace across the entire width of the same, by the now stationary follower or scraper. Finally, the camming devices 28 engage the 20 lugs 27 and throw the stops inwardly out of the path of the fingers 23, thereby releasing the scraper; whereupon the latter is immediately retracted while the rest of the charging frame is completing its rearward movement. The parts are thus restored to their initial positions, ready for another charge.

It will be observed that the charging pan conforms in size and contour to the plan of 30 the furnace, so that the materials which are to be burned can be placed on the pan in the positions which they are to occupy in the furnace. Then as the pan is withdrawn the materials pour over the forward edge 35 and settle gently into these positions.

It is to be understood that the invention is not limited to the construction herein specifically shown and described, but may be embodied in various forms without departing 40 from its proper spirit and scope.

I claim:

1. In a furnace-feeding apparatus, in combination, an open receptacle, a follower movable therein, retracting rods connected 45 with the follower, a ram connected with the receptacle to advance and retract the same,

a member rigidly connected with the receptacle, stops mounted on said rods and arranged to be engaged by the said member in the forward movement of the receptacle 50 whereby to advance the follower, means arranged to engage the follower and hold the same stationary in its advanced position, means connected with said rods to retract the follower, and means for releasing the 55 follower from said holding means to permit retraction of the follower by the said reTRACTING means.

2. In a furnace-feeding apparatus, in combination, a receptacle having rearwardly extending side members, a cross member secured to the side members in the rear of the receptacle, means connected with said cross member to advance and retract the receptacle, a scraper movably mounted 60 in the receptacle, rods connected to the scraper and extending rearwardly past the said cross member, stops mounted on the rods in front of the cross member and adapted to be engaged thereby to advance 65 the scraper with the receptacle, releasable means for holding the scraper stationary in its advanced position, and means connected with the said rods to retract the same and the scraper upon release of the said holding 70 means.

3. In a furnace-feeding apparatus, a receptacle, means for advancing and retracting the same, a scraper mounted in the receptacle and movable therewith in the forward movement of the same, rearwardly swinging fingers connected with the scraper, transversely swinging stops in the path of 80 said fingers, and means carried by the receptacle for swinging said stops out of the 85 path of the fingers.

In testimony whereof I affix my signature in the presence of two subscribing witnesses.

JOHN T. FETHERSTON.
